UNITED STATES PATENT OFFICE.

ELMER A. ELY, OF MIDDLETOWN, CONNECTICUT.

DECK-PLATE.

No. 829,862.

Specification of Letters Patent.

Patented Aug. 28, 1906.

Application filed February 9, 1906. Serial No. 300,256.

To all whom it may concern:

Be it known that I, ELMER A. ELY, a citizen of the United States, residing at Middletown, in the county of Middlesex and State 5 of Connecticut, have invented a new and useful Deck-Plate, of which the following is a specification.

This invention relates to those articles which are primarily designed for the purpose 10 of covering and protecting openings through the decks and floors of boats, but which are useful in other places where it is desirable to provide holes with tight but easily-removable covers.

15 The object of the invention is to provide a very simple and cheap article of this nature which can be quickly and conveniently applied to the deck or floor of a boat or other structure in such manner that the opening 20 may be tightly closed to prevent the entrance of water or quickly opened to allow access through it.

The device illustrated in the accompanying drawings as embodying the invention 25 has an annular frame that is designed to be permanently attached to the deck or floor about the opening and a plate that fits the frame and has a spring-bolt for fastening the parts together and means for releasing the 30 bolt when it is desired to remove the plate from the frame.

Figure 1 of the views shows a plan of the plate and the frame fastened together as in use. Fig. 2 shows a bottom view of the frame. 35 Fig. 3 shows a bottom view of the plate, and Fig. 4 shows a diametrical section of the plate and frame.

The frame 1 is preferably an annular piece 40 of metal with perforations for the screws which are used for the purpose of fastening the frame on or in the deck or floor about the opening. Extending inwardly from the inner edge of the frame is an annular flange 2, and in this flange, on diametrically opposite 45 sides, are sockets 3. The flange is designed to fit the opening and the annular plate to rest upon or to be let into the deck or floor about the opening. The plate 4 is preferably circular and a little smaller in diameter than the 50 diameter of the frame. Extending downwardly from the under side of the plate is a flange 5, which is slightly smaller than the opening through the flange of the frame. On the under side of the plate is a chamber, and lying in this 55 chamber and having one end extending

through the flange is a bolt 6. A spring 7 tends to thrust this bolt so that its end will project out through the flange. Connected with the bolt and extending upwardly through the plate is a stud 8, that is attached to a button 9, 60 which lies upon the upper surface of the plate. By moving this button the bolt may be drawn back into the chamber against the thrust of the spring. Projecting outwardly from the flange diametrically opposite to the projecting 65 end of the movable bolt is a fixed stud 10.

In use the frame is fastened by screws or bolts to the deck or floor about the opening to be covered. The plate is attached to the frame by thrusting the fixed stud that projects from the flange of the plate into one of the sockets in the flange of the frame and then forcing down the other side of the plate until the end of the spring-bolt snaps into the other socket in the frame-flange. This holds 70 the plate and the frame tightly together. If desired, a packing 11, of rubber or other material, may be placed on the under side of the plate about the flange for the purpose of making the joint tight when the parts are 75 together.

In order to open the plate, the button is pulled or pushed back so as to draw the spring-bolt within the chamber. The released edge of the plate is then tipped upwardly until the edge of the flange on the plate is out of the opening through the frame. Then the plate may be drawn forwardly and upwardly until the stud is drawn from the rear socket, after which the plate can be lifted 85 clear from the frame. These plates are more particularly used for covering deck-openings above gasolene-tanks, water-tanks, or pump-outlets, but of course they may be used for other purposes. 90

The plate described is cheap to make, simple to apply, and can be opened and closed easily and quickly, either in the daylight or dark, and requires no key such as is used with the common deck-plates which are screwed 95 to and from place.

The invention claimed is—

A deck-plate comprising an annular frame having an inwardly-extending annular flange with perforations diametrically opposite each other through the flange, a circular plate having an inwardly-extending annular flange with perforations diametrically opposite each other through the flange and a slot through the center of the plate, a fixed stud project- 105 110

ing through one perforation in the plate-flange and into one frame-flange perforation, a movable bolt projecting through the other perforation in the plate-flange and into the
5 other frame-flange perforation, a spring forcing the bolt outwardly, a stud extending from the bolt through the slot in the center of

the plate and a button fastened to the stud and covering the slot, substantially as specified.

ELMER A. ELY.
